UNITED STATES PATENT OFFICE.

J. J. L. ROUSSEAU DE LAFARGE, OF PARIS, FRANCE.

APPARATUS FOR OBTAINING PHOTOGRAPHIC PICTURES.

Specification forming part of Letters Patent No. 43,270, dated June 21, 1864.

To all whom it may concern:

Be it known that I, JEAN JACQUES LEOPOLD ROUSSEAU DE LAFARGE, of Paris, in the Empire of France, have invented certain new and useful Improvements in Photographic Apparatus; and I do hereby declare that the following is a full, clear, and exact description of the same, reference being had to the accompanying drawings.

This apparatus enables the manipulator to operate in full light upon damp collodion to sensitize the glass and to finish the proof in the light.

The apparatus does not alter the negative now used, but it serves as an auxiliary to it. In the apparatus the following characteristic elements are combined: The employment of two vertical and independent bath-vessels arranged to allow of the glasses being easily plunged therein. One vessel, containing the bath of silver for sensitizing the damp collodion, may be of gutta-percha, hardened rubber, or other material having no action on the bath. The other, containing the iron bath for developing the picture, should be of yellow or orange colored glass. If made of any other material, it should be lined with yellow-colored glass. There is a frame for holding the glasses to be exposed, capable of being opened and closed at bottom by withdrawing or inserting a sliding bar. There is a second frame for holding the collodionized glass in the former frame, which second frame is styled the "plunging-frame," because it is used for introducing the glass into the bath-vessels, entering also with it. It is insulated from the first frame, and may be passed through it. A piece of catgut is attached to the plunging-frame to raise and lower it into and out of the baths.

The arrangement of the apparatus and the method of action will be fully understood on reference to the accompanying drawings and the following description: The apparatus is composed of a grooved box, *a*, Figure 1, for carrying the glasses, at the back of which is a compartment, *b*, for the bottles, Fig. 2. To this box two vertical vessels, *c c*, are attached by pins and gudgeons *d d*, Figs. 1 and 2, and a hook, *e*. A straight rod entering the hole *g*, Fig. 2, makes the attachment firm. There is a groove in the upper part of the vessels *c c*, of the breadth of the principal frame, herein-

after mentioned, to receive the frame during the operation. To hold it the vessels are fitted with two plates projecting a little over the opening *y y*, Fig. 3. The groove in each vessel is closed on one side, *k*, Fig. 1. On the other it may be closed by a hardened-rubber spring, Fig. 17. The opening of each vessel is closed by a stopper, *f*, Figs. 1 and 3, fitted with an india-rubber band. Pressure is exerted and maintained by two screws, *i i*. As before stated, the vessel for containing the nitrate-of-silver bath should be of water-proof material and should exert no action upon the bath. I prefer gutta-percha or glass. It should also be inclosed by a wooden frame. The vessel for developing the picture should be of yellow or orange colored glass. If made of any other material it should be lined with yellow-colored glass.

Fig. 21 represents a square piece of cork fixed to a small rod, with two lines thereon for indicating the minimum and maximum quantity of liquid to be introduced into each vessel. Fig. 3 is a side view of one of the vessels open. Fig. 4 represents the frame which exposes the glasses to the dark-chamber, and for stereoscopic proofs. I call it the "principal" or "outer" frame. Its lower part is opened and closed at will by means of a rod, *X*, of whale-bone, wood, or hardened rubber, sliding in a grooved guide. *p p* is another exterior groove having a corresponding groove parallel and at the same height on the other face.

Fig. 5 shows a second frame for holding the collodionized glass in the former frame, which second frame, as before stated, is styled the "plunging-frame." It is formed of bands of copper or brass of the same breadth and thickness, soldered together, as seen in the figure. The bands *a a* are seen in side view, and the bands *b b* in front view. *c* shows the latter in side view. Small clips *V V* are soldered at *z z*, and serve to hold the glass and insulate it from the bands *b*. A space is left for the easy passage of the liquid. At the corresponding upper part there are also fixed two small plates, *y y*, as seen at *t*, or simply of the shape represented at *g*. They also insulate the glass, which thus rests only upon its four corners. The plunging-frame is itself kept as much as possible from contact with the principal frame by four other soldered pieces or

shoes, *r r r r*, a little bent, as shown at *s*. A small button, *f*, moving round a pin, assists in holding the glass. The whole should be silvered. The plunging-frame is moved from the principal frame into the bath-vessels, and vice versa, by means of a piece of catgut passing to the outside through a hole, *m*, formed in the upper part of the principal frame, Fig. 4. Fig. 24 shows a plunging-frame with a different arrangement of the shoes *r r r r*. Fig. 7 is another plunging-frame of hardened rubber. Fig. 6 shows the plunging-frame moving in the principal frame.

The spring which presses on the glass to keep it in position is represented in Fig. 20. *a b* shows a flap in side view, in which a recess is formed to receive two copper plates, *rr*, and two steel springs, *ss*. The two copper plates are fixed in the flap by two axes at the points *t t*. They are connected hingewise at *u*, and at this point they are also connected to a rod which communicates outside with a button, *V*. When pressure is exerted on this button, the two plates move on their respective axes and enter the thickness of the flap. The rod of the button is retained in this position by a spring-bolt, which seizes it. If the copper plates are to be allowed to pass onto the glass, simply draw the spring-bolt, and the two springs *ss*, being free, exert their pressure and push the button outward.

If the principal frame for stereoscopic proofs has two flaps underneath, that of the lower part should have a handle in the form of a **T**, entering at will. (See Fig. 14.)

The manipulations are performed as follows: The principal frame inclosing the plunging-frame is fitted to the vessel containing the nitrate of silver. The plates *y y*, Fig. 3, take into the grooves *p p*, Fig. 4, and the frame slides along the opening in the vessel. (This arrangement may be replaced by a dovetail-groove and corresponding dovetail projection, as represented in Figs. 8 and 23.) The flap of the frame is then opened, the glass collodionized, and introduced into the plunging-frame. The flap is then closed, care being taken that its spring re-enters the thickness thereof, the rod *X* is drawn out, and the glass consequently falls into the vessel. After it has been sufficiently sensitized it is raised into the principal frame by drawing the string. The opening of the principal frame is closed by returning the rod *X* to its place. The spring-bolt is then drawn and I expose to the dark-chamber. For the development of the image the frame is applied to the vessel containing protosulphate of iron, and the glass is submitted to the bath in the same manner as to the nitrate-of-silver bath, with this difference, that it is made to turn on hinges so as to show by transparency the development of the image. It is then only necessary to wash and fix.

If desired, other vessels may be fitted between those previously mentioned and the

box *a*, Fig. 1. Before commencing another proof the traces of the iron bath are removed from the frame.

Fig. 9 shows the plunging-frame in the act of being lowered from the principal frame into a vessel, *c*, Fig. 15. In order that this may take place freely the internal breadth of the principal frame should be narrower than the vessel and the lower opening of the principal frame should be widened and rounded at the edges.

The plunging frame may be dispensed with by employing a screwed nipper of silver, as represented in front and side views in Fig. 19. It takes hold of the glass at the upper part. A piece of india-rubber prevents the screw from rubbing against the glass. The methods represented in Figs. 18 and 22 may also be adopted. In these arrangements the glass moves in grooves formed by rabbets *a b a b* on the frame and two fillets fixed to the interior surface of the door. (See Figs. 10 and 11.) The rabbets *a b a b* are on a level with the rabbit *c d* the same at the lower part of the frame. By the addition of fillets I can form these rabbets, if desired, in the frame of the preceding arrangement.

Fig. 16 represents the internal grooves in which the glass works and the passage for the nipper or hooks. At the lower part of the principal frame the rabbets *a b a b* and the two fillets should be rounded off, as shown in Figs. 12 and 26. In Fig. 26 the fillets are held by screws. The vessels do not require any modification. They may, however, if desired, have small fillets fitted to them similar to those in Fig. 12, or two fillets in the form of triangular prisms, two sides of which are rounded where they meet the third side. The opening of the vessel is modified, as shown at *r*, Fig. 25. In these last arrangements, before sensitizing the glass it is necessary to remove with a piece of paper about a sixth of an inch of collodion from the side edges.

Fig. 13 shows how this invention may be applied to all kinds of dark-chambers. It is only necessary to retain the plate *t*, shown detached at *g*.

And, having now described the nature of the said invention, and in what manner the same is to be performed, I declare that I claim—

1. The internally grooved box for carrying the glasses, in combination with compartments at the back thereof for holding the bottles.
2. In combination with the double glass and bottle-box, the pintles and gudgeons at the sides thereof for the attachment thereto of two vertical and independent bath-vessels, one lined with rubber or the equivalent thereof to contain the silver bath for sensitizing the damp collodion, the other made or lined with yellow glass to contain the iron bath for developing the picture.
3. Combining with each vessel a hinged

flap provided with a rubber or rubber-lined stopper and screws to form a secure and hermetic joint, substantially as set forth.

4. The construction of the principal or outer frame with plunging-frame or nipper and doors provided with springs for keeping the glass in position.

5. The arrangement of the springs in the flap and their combination with an outside knob and trigger, so that the springs may be

withdrawn from off the surface of the glass or released at pleasure, substantially in the manner and for the purposes set forth.

In testimony whereof I have signed my name to this specification before two subscribing witnesses.

J. J. L. ROUSSEAU DE LAFARGE.
